(57) **CLAIM**

The ornamental design for a speaker storage bag, as shown and described.

DESCRIPTION

FIG. 1 is a front perspective view of a speaker storage bag, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view showing the speaker storage bag in a use state.

The broken lines in the drawings illustrate the portions of the speaker storage bag, which form no part of the claimed design. The broken lines showing an attachable shoulder strap in FIG. 9 is included for the purpose of illustrating environmental subject matter that forms no part of the claimed design.

1 Claim, 9 Drawing Sheets
